SEAMING ROLLS FOR SECURING ENDS ON CAN BODIES

Robert Ernest Geeson, Croydon, England, assignor to The Metal Box Company Limited, London, England, a British company

Filed Feb. 18, 1959, Ser. No. 794,144

Claims priority, application Great Britain May 30, 1958
5 Claims. (Cl. 113—24)

This invention relates to seaming rolls for securing ends on can bodies.

One problem which is always encountered when seaming ends on can bodies made from flat blanks is to provide for the relief of pressure, particularly during the second seaming operation, when a seaming roll passes over the side seam formed in the can body, it being understood that seaming is usually effected by what are known as first and second seaming operations. Heretofore it has been customary to employ springs in an attempt to overcome this problem but as the springs also perform other functions if combined with other essential elements or, if not combined, usually create an undesirably heavy mass, such proposals have not resulted in an adequate solution to the problem with the result that the end seam formation tends to be uneven in form and tightness in the region of the side seam of the can body. It is the main object of the present invention to provide a seaming roll the construction of which is such as to ensure a substantially even and uniformly tight end seam while avoiding the use of conventional springs which must serve more than one purpose or suffer from the disadvantage of heavy mass.

According to the present invention a seaming roll for securing ends on can bodies comprises a spindle adapted for rotation about its longitudinal axis, a peripherally grooved annular element supported for rotation with said spindle and for lateral movement relative thereto in a direction at right-angles to said axis, and locating means tending to maintain said element concentric with said axis.

In order that the invention may be clearly understood one embodiment thereof will now be described, by way of example, with reference to the accompanying drawings in which:

FIG. 1 illustrates a part of a seaming mechanism having a seaming roll according to the invention applied thereto,

FIG. 2 is a section through the seaming roll, and

FIG. 3 is an underneath plan of an annular element forming part of the seaming roll.

Referring to the drawings, the seaming roll 1 is supported by one arm 2 of a pair of arms secured to a stub shaft 3, FIG. 1, for rocking movement about the axis of shaft 3 in a seaming roll support 4 rotatable about the axis of a chuck 5. The other arm 6 of the pair supports a pair of frusto-conical cam followers 7, 8 which co-operate respectively with cams 9, 10 to cause the seaming roll to follow a path which conforms to the contour of the chuck, and to apply the seaming pressure to the seaming roll. This apparatus forms no part of the present invention as a seaming roll according to the invention can be applied to other forms of mechanism designed to function in a similar manner.

The seaming roll, FIG. 2, comprises an annular element the periphery of which may be provided with a first seaming operation groove 11 and a second seaming operation groove 12, or if desired, with only a second seaming operation groove. The annular element is supported for rotation with a spindle 13 which in FIG. 2 is journaled in the arm 2 to be freely rotatable about its longitudinal

2

axis. The annular element is also movable laterally relative to the spindle in a direction at right angles to the axis of the spindle and locating means are provided to tend to maintain the annular element concentric with the axis of the spindle.

The locating means comprises a washer 14 which, as can be seen from FIG. 2, is located between the annular element and the spindle, and balls 15 which are seated between the opposite sides 18, 17 of the annular element and resilient annular plates 18, 19 co-axial with the spindle 13 and stressed to urge the balls 15 to the seated positions thereof.

The ball-seatings are formed by counter-sinking holes 20 as at 21, 22, the counter-sinking for alternate holes being formed alternately in the said sides 16, 17. The plates 18, 19 are also provided with countersunk seatings at positions adjacent to the peripheries thereof.

The plates 18, 19 are clamped relative to the spindle 13 in a manner such that they converge towards the spindle 13 to effect stressing thereof and to this end the plate 18, 19 are spaced apart by the washer 14 and are clamped between a shoulder 23 and a nut 24 on the spindle 13. As can be seen from FIG. 3, the ball-seatings 21, 22 are displaced angularly with relation to each other.

25 In operation, while the seaming pressure remains constant the annular element remains concentric with the axis of the spindle 13. When, however, the seaming pressure tends to exceed that normally applied, as when during the second seaming operation the seaming roll passes over the side seam formed in the can body, the excess pressure overcomes the pre-load exerted by plates 18, 19 so that the balls ride partially out of their seats and permit lateral movement of the annular element thus maintaining the seaming pressure substantially constant as 30 the roll rides over the can body side seam. As the roll rides off the side seam the stress in plates 18 and 19 restores the balls to their seats and the annular element to the position thereof in which it is concentric with the axis of spindle 13.

40 I claim:

1. A seaming roll for securing ends on can bodies, comprising a spindle adapted for rotation about its longitudinal axis, a peripherally grooved annular element encircling said spindle and supported for rotation with said spindle and for lateral movement relative thereto in a direction at right-angles to said axis, and locating means tending to maintain said element concentric with said axis, said locating means comprising a pair of annular plates co-axial with the spindle and spaced apart axially therefrom by a washer, and balls seated between the opposite sides of the annular element and said plates and being rideable thereoutof to permit limited lateral movement of said annular member, the plates being stressed to urge the balls to the seated positions thereof.

50 2. A seaming roll according to claim 1, wherein the ball-seatings are formed in sides of said annular element and in said plates at positions adjacent to the peripheries of the plates, and the plates are clamped relative to the spindle in a manner such that they converge towards the spindle to effect said stressing thereof.

60 3. A seaming roll according to claim 1, wherein the ball-seatings formed in one side of the annular element are displaced angularly with relation to those formed in the opposite side of the annular element.

65 4. A seaming roll comprising a spindle, means mounting said spindle for rocking movement into and out of a can seaming position, an annular seaming member encircling said spindle, said seaming member having an opening therethrough larger than a corresponding portion of said spindle to permit limited lateral movement of said seaming member relative to said spindle in a direc-

tion at right angles to the longitudinal axis of said spindle, and combined connecting and locating means disposed between said spindle and said seaming member for connecting said seaming member to said spindle for rotation therewith and for resiliently urging said seaming member to a position concentric with said spindle axis.

5. A seaming roll comprising a spindle, means mounting said spindle for rocking movement into and out of a can seaming position, an annular seaming member encircling said spindle, said seaming member having an opening therethrough larger than a corresponding portion of said spindle to permit limited lateral movement of said seaming member relative to said spindle in a direction at right angles to the longitudinal axis of said spindle, a shoulder on said spindle and clamp means on said spindle opposing said shoulder, first and second spring plates abutting said shoulder and said clamp member, respectively, said spring plates being disposed on opposite sides of said seaming members, a washer disposed within said
